UNITED STATES PATENT OFFICE.

ROBERT ELWOOD ELLIS, OF SEATTLE, WASHINGTON.

SCOW HULL CONSTRUCTED OF CHANNEL SHAPES.

Application filed December 21, 1925. Serial No. 76,723.

My invention relates to a scow hull constructed of channel shapes.

The particular type of a ship known as a scow is peculiarly subject to great strains due to its extreme shallowness in comparison to its breadth and length, and also due to the lack of uniformity in disposition of the load. In loading a ship, great care is taken to load the same uniformly, so that the weight is balanced and the vessel is kept in trim, thereby placing no undue strains upon the hull. The exact opposite condition obtains for a scow. A scow may be placed under a chute for loading, and one side or end may be heavily loaded, with the result that the vessel may be disposed at a big angle to the surface of the water, or she may trim by bow or stern,—all of which produces abnormal strains on the structure. A further complicating factor is that the structure must sustain the towing strains while supporting the load,—a condition which, of course, is not ordinary in the case of a ship.

Furthermore, a scow is subject to particularly severe shocks arising when the tugs, which tow or push the scow from one place to another, strike or ram into the scow hull to shove it sidewise, or endwise. In all these ways, as well as others, a scow hull is subject to especially rough usage.

Ordinarily a scow must be of shallow draft and economical in construction, as well as of great strength. According to present practice and design, scows are generally constructed of wood. Serious objection obtains to wooden construction in that the same gradually becomes water-soaked, so that it is customary to allow a high percentage or reduction in their carrying capacity depending upon the age of the structure. This must be considered when the scow is dispatched to receive a load and constitutes a large element in calculating its depreciation and loss in efficiency. While a scow made of metal, such as iron or steel, overcomes this objection, nevertheless the great cost of steel construction heretofore has proven such a handicap that the more general construction for scows has been wooden. Another objection to wooden hull construction is that it becomes deformed or "hogged", due to the fact that the hull is much heavier per unit of length at the ends than in the portion intermediate the ends. This normally places the deck under

tension and the bottom under compression. Therefore, a primary object of my invention is to provide a metal hull construction which will overcome these objections and be light so as to be of shallow draft and yet of such strength as to meet the severe requirements imposed by the conditions of scow operation.

The particular metal construction unit known as a channel shape is desirable for hull construction for some reasons, particularly since they may be secured together along their flanges which may be disposed inwardly of the hull, and the riveting, which may be employed in holding the same together, may thus be kept from being exposed to the water for the most part. Said flanges also constitute stiffening ribs which permit of providing the necessary strength and stiffness and at the same time eliminate both by weight as well as by number much of the transverse frame members, and in the construction herein set forth eliminate entirely the longitudinal framing. In this wise, lightness of construction is obtained, which ordinarily must characterize a scow so that it may operate in shallow water and carry its maximum load. Channel shapes are a market article which may be employed throughout an entire hull and be in general of one width, (subject to the variations hereinafter to be noted as to exact width). This results in eliminating the great cost of handling and assorting and butting, which increases the cost so greatly in flat plate construction. At least, the sizes of the channel shapes may be so limited in number for a given hull that little or no objection arises by reason of handling and assorting, while butting is eliminated altogether.

However, serious objection has obtained to the employment of said channel shapes due to their varying width, and so serious has this objection been that the adoption of channel shapes as a construction unit has been postponed so far as their use is concerned in hull construction. The obvious manner of overcoming this objection, namely, by using liners, so greatly increases the cost that little advantage would remain in adopting such units of construction. The variation in width of the channel shapes arises by reason of the fact that the temperature of the rollers at the rolling mill vary. A primary object of my invention is to

overcome this objection occasioned by the variation in widths of the channel shapes and eliminate the use of liners.

The above mentioned general objects of my invention, together with others inherent in the same, are attained by the device illustrated in the following drawings, the same being merely preferred exemplary forms of embodiment of my invention, throughout which drawings like reference numerals indicate like parts:

Figure 1 is a view in cross section from amidship to the side of a scow hull structure embodying my invention;

Fig. 2 is a fragmentary view in side elevation of said scow embodying my invention;

Fig. 3 is a view in cross section of an end portion of a scow embodying my invention;

Fig. 4 is a fragmentary deck view of a scow embodying my invention.

Channel shapes 5 extending from one end of the vessel to the other are disposed side by side with their flanges riveted together which form ribs 6, preferably longitudinally disposed of the vessel. These channel shapes are caused to extend laterally on both sides from the midship section 7, 7. Likewise, channel shapes 8 are employed to form the sides of the scow hull and extend from one end to the other. The lateral-most channel shape on each side in the bottom is in spaced relation to the bottom-most channel shape on the side, and the side and bottom are then connected by means of a bilge plate 9 extending the full length of the vessel and up the rakes. This placing the said channel shapes in spaced relation provides for taking up any discrepancies in width that may result from the difference in width of the channel shapes. It must be remembered that said channel shapes may vary considerably in width, even though a given size be ordered, owing to the fact that the rollers at the steel mill vary in width due to the variations in temperature incident to the manufacturing process.

The deck is formed of channel shapes 10 having their flanges preferably turned inwardly to present a smooth deck surface. Obviously, transverse frame members 11, 12 and 13 with lattice framing members 14, 15 and 16 form a transversely disposed truss member which supports the sides and bottom and deck. Corner plates 18 serve to make more rigid the attachment of these transverse frame members. Notches 28 in the transverse members provide openings for the ribs 6.

It will be noted that there are no longitudinal frame members of the character such as employed for the transverse truss members. In short, it is the rib members formed by the flanges of the channel shapes 5 and the channel shapes 10 which particularly

provide for the longitudinal stiffening, so that the units which constitute the hull wall also are employed to constitute the longitudinal stiffening members. This eliminates the great weight of the longitudinal keel-sons without lessening the strength of the vessel, and by eliminating the weight not only is the scow made much cheaper, but also it is made much lighter, and therefore a shallowness of draft is provided, which enables the scow to carry a maximum load. It must be remembered that lightness of weight is most important in a scow, which must be enabled to approach close to shore and operate most frequently in very shallow water. The lateral bearing of the flanges also provides for a lateral stiffening which assists in keeping the weight reduced to a minimum.

Channel shapes 19 (see Fig. 3) are disposed athwartship to form the rakes, and a channel shape 20 is disposed athwartship to constitute the end member and is preferably provided with a bracing angle 21. Plates 22 connect the bottom and rake, and plate 23 connects the rake and the end member 20, while plate 24 joins the deck channel shapes 10 with the end member 20. Plate 25 joins the side channel shapes to deck shape 26, which is preferably a channel shape with one flange removed. The disposing of the sides of the hull and the channel shape 26 in spaced relation provides for taking up any discrepancies in width, which may occur in the channel shapes 10 forming the deck. Plate 25 is preferably caused to extend well down the side of the scow, so that it may function as a protector plate. Corner pieces 27 may be employed to protect the deck corners.

The mode of operation of a scow embodying my invention has been explained above in connection with its construction. It is manifest that the elimination of the longitudinal framing members provides for a very much cheaper steel construction, and it is manifest that since the deck is normally under tension and the bottom under compression, advantage may be well taken of this fact in providing the hull to be made of channel shapes, the flanges of which shapes are caused to constitute longitudinally disposed ribs which function as longitudinal bracing members. At the same time weight is eliminated, with the all-important advantage in a scow construction of providing for a shallow draft. Having the channel shapes 5 extend to the rakes and the deck channel shapes 10 extend full length of the vessel, and likewise the channel shapes 8 forming the sides and extending from rake to rake, eliminates all difficulties arising by reason of connecting the channel shapes as respects their end portions. A number of scows now actually constructed and in operation es-

tablishes beyond any question of a doubt the importance of the advantages herein noted.

Obviously, changes may be made in the form, dimensions and arrangement of the parts of my invention, without departing from the principle thereof, the above setting forth only a preferred form of embodiment.

10 I claim:

1. A scow embodying a hull substantially square in vertical cross section at all transverse planes, formed of channel shapes, said shapes extending lengthwise along the sides and bottom of the hull, said sides and bottom being in spaced relation; rakes which are in spaced relation to the bottom; a bilge plate on each side connecting the side and bottom, said plate extending along the bottom and up the rakes; plates extending transversely of the hull connecting said rakes and bottom; transverse trusses secured to the sides, bottom and deck, the

flanges of the channel shapes being secured together and constituting exclusively the 25 longitudinal framing, whereby is provided a scow characterized by its strength and lightness of weight and shallowness of draft.

2. A scow substantially square in vertical 20 cross section at all transverse planes, having a deck, bottom, rakes and sides composed of longitudinally extending channel shapes, the flanges of which are riveted together, the terminal side, bottom and rake shapes 25 being spaced apart; bilge plates extending along the bottom and up the rakes, said plates connecting said bottom and sides, and said sides and rakes; plates connecting the rakes and bottom; and transverse trusses secured to sides, deck and bottom, said channel shape flanges constituting exclusively the longitudinal framing.

In witness whereof, I hereunto subscribe my name this 19th day of December, 1925.

ROBERT ELWOOD ELLIS.
